UNITED STATES PATENT OFFICE.

GEORGE W. MILLER, OF WOONSOCKET, RHODE ISLAND.

MACHINE FOR PRESSING FABRICS.

SPECIFICATION forming part of Letters Patent No. 361,773, dated April 26, 1887.

Application filed July 1, 1886. Serial No. 206,832. (No model.)

To all whom it may concern:

Be it known that I, GEORGE W. MILLER, a citizen of the United States, and a resident of Woonsocket, in the county of Providence and 5 State of Rhode Island, have invented certain new and useful Improvements in Machines for Pressing Fabrics, of which the following is a specification.

My invention relates to that class of beds 10 used in machines for pressing fabrics; and it consists in constructing the bed and the facing of thin metal, so that the latter can be applied to and removed from the bed longitudinally to avoid the necessity of removing the bed or 15 unduly elevating the cylinder to effect such application and removal.

In the drawings, Figure 1 is a sectional elevation showing the cylinder and opposite beds of a cloth-pressing machine with the facings 20 thereon and illustrating my improvement. Fig. 2 is a side view of part of the cylinder and beds, showing in section a part of the frame of the machine as constructed to carry out my invention. Fig. 3 is a transverse section on the line 1 2, Fig. 2, the frame of the 25 machine being shown in dotted lines. Fig. 4 is a transverse section of a bed and facing illustrating a modification.

In pressing-machines as usually constructed 30 it is common to use beds, single or double, with thin metal facings or linings, which are secured to the faces of the beds, and which can only be removed by detaching the bed or elevating the roller. This is not only inconvenient, but results in delays, and sometimes in 35 improper adjustments of the linings and injury to the fabrics. To avoid these and other objections, I secure the facing to the bed, so as to be longitudinally removable therefrom, and 40 construct the frame to permit such removal without displacing the bed or elevating or moving the roller farther than is necessary to take the friction off of the facing.

The bed and facing may be constructed in 45 different ways, so as to secure an attachment along the opposite edges of the facing, and yet permit longitudinal detachment. Thus in Fig. 1 the lower bed, A, is shown as provided with edge flanges *a a*, and the lining B, which con-

forms to the curved face of the bed, also conforms to the flanges and extends over and has flanges *b*, which catch beneath the flanges *a*, so as to hold the lining in place on the bed and prevent lateral movement or lifting of the lining from the bed, yet permit longitudinal 50 movements.

The side frame, C, has an opening, *x*, opposite the end of the bed A, of such shape as to permit the longitudinal insertion and withdrawal of the facing, and the latter is secured 55 in place after adjustment by means of a single screw-bolt, *e*, or other suitable securing device.

The facing B of the upper bed, E, is shown in Fig. 1 as being held in position on the bed by edge flanges engaging with flanges of the 60 bed. In Fig. 4 is shown a modification, in which the edge flanges of the facing extend laterally into grooves in the bed, the facing being secured against longitudinal movement by a screw-bolt, *e*.

I have shown only the parts of the pressing-machine adjacent to the beds, as my invention relates only to the latter and its facing, and is applicable to pressing-machines of various 65 constructions.

Without limiting myself to the precise construction and arrangement of parts shown, I claim—

1. The combination of a pressing-machine bed having edge bearings and a longitudinally-removable thin metal facing having edge flanges engaging with said bearings to prevent the facing from being lifted from the bed, substantially as described.

2. A pressing-machine bed having edge 80 flanges and a thin metallic facing conforming to the bed and extending over said flanges, and with edge flanges overlapping the flanges of the bed to hold the facing thereon, substantially as described.

In testimony whereof I have signed my name to this specification in the presence of two subscribing witnesses.

G. W. MILLER.
